(57) **CLAIM**

We claim the ornamental design for a firearm handguard, as
shown and described.

DESCRIPTION

FIG. 1 is a top front perspective view of a firearm handguard
of a first length according to the present invention;

FIG. 2 is a bottom rear perspective view of the firearm
handguard of FIG. 1.

FIG. 3 is a front view of the firearm handguard of FIG. 1;
FIG. 4 is a left side view of the firearm handguard of FIG.
1;

FIG. 5 is a rear end view of the firearm handguard of FIG.
1;

FIG. 6 is a right side view of the firearm handguard of FIG.
1;

FIG. 7 is a top view of the firearm handguard of FIG. 1;
FIG. 8 is a bottom view of the firearm handguard of FIG. 1;

FIG. 9 is a top front perspective view of a firearm handguard
of a second length according to the present invention;
FIG. 10 is a bottom rear perspective view of the firearm
handguard of FIG. 9.

FIG. 11 is a front view of the firearm handguard of FIG. 9;
FIG. 12 is a left side view of the firearm handguard of FIG.
9;

FIG. 13 is a rear end view of the firearm handguard of FIG.
9;

FIG. 14 is a right side view of the firearm handguard of FIG.
9;

FIG. 15 is a top view of the firearm handguard of FIG. 9;
and,

FIG. 16 is a bottom view of the firearm handguard of FIG.
9.

The portions of the firearm handguard shown in broken lines
are included for the purpose of illustrating environment and
form no part of the claimed design. Claim
